UNITED STATES PATENT OFFICE.

AUGUSTUS J. HARPSTRITE, OF LOS ANGELES, CALIFORNIA.

DESIGN FOR AN AIRSHIP.

Application filed August 1, 1927. Serial No. 22,969. Term of patent 3½ years.

To all whom it may concern:

Be it known that I, AUGUSTUS J. HARPSTRITE, a citizen of the United States, and resident of Los Angeles, California, have invented a new, original, and ornamental Design for an Airship, of which the following is a specification, reference being had to the accompanying drawing, forming a part hereof.

Figure 1 is a front elevation.

Figure 2 is a side elevation.

Figure 3 is a plan of the article, showing my new design.

I claim:

The ornamental design for an airship substantially as shown.

AUGUSTUS J. HARPSTRITE.
